UNITED STATES PATENT OFFICE

169,460

OVER-BED TABLE

Lee Smith, Ludington, Mich.

Application June 14, 1952, Serial No. 20,190

Term of patent 14 years

(Cl. D33—14)

To all whom it may concern:

Be it known that I, Lee Smith, whose full and correct name is Lee Smith, a citizen of the United States, residing in the city of Ludington, county of Mason and State of Michigan, have invented a new, original, and ornamental Design for an Over-Bed Table, of which the following is a specification, references being had to the accompanying drawings, forming a part hereof.

Fig. 1 is a perspective view of an over-bed table embodying my new design and displayed with its concealable slide mirror in utility position;

Fig. 2 is a perspective view of the same article with the slide mirror concealed;

Fig. 3 is a plan view of the same article with its end drawer partially extended;

Fig. 4 is an end elevational view thereof;

Fig. 5 is a side elevational view thereof; and
Fig. 6 is a fragmentary sectional view taken approximately on the line 6—6 of Fig. 1.

The dominant features of my design reside in those portions shown in full lines.

I claim:

The ornamental design for an over-bed table,
as shown and described.

LEE SMITH.
